DECORATIVE PROTECTIVE HOUSING FOR ELECTRICAL FIXTURE

Jack A. Meltzer, 3398 Fairway Road,
Oceanside, N.Y. 11572

Filed Apr. 12, 1968, Ser. No. 11,442

Term of patent 14 years

Int. Cl. D26—02

U.S. Cl. D48—16

FIGURE 1 is a front perspective view of the decorative protective housings for electrical fixture embodying my new design; and

I claim:

The ornamental design for a decorative protective housing for electrical fixture, substantially as shown.
